UNITED STATES PATENT OFFICE.

CONRAD ROBERT ANDERSON, OF WEST DULUTH, MINNESOTA.

RATCHET WRENCH.

959,690.

Specification of Letters Patent. Patented May 31, 1910.

Application filed December 9, 1909. Serial No. 532,232.

To all whom it may concern:

Be it known that I, CONRAD ROBERT ANDERSON, a citizen of the United States, residing at West Duluth, in the county of St. Louis, 5 States of Minnesota, have invented certain new and useful Improvements in Ratchet-Wrenches; and I do hereby declare the following to be a full, clear, and exact description of the invention, such as will enable 10 others skilled in the art to which it appertains to make and use the same.

This invention relates to ratchet wrenches.

The object of the invention is the production of a ratchet wrench which is simple 15 and cheap in construction and highly efficient in use, and to this end the invention consists in the combination and arrangement of parts to be hereinafter more fully set forth and described.

20 In describing the invention in detail reference will be had to the accompanying drawings in which like characters of reference denote corresponding parts in the several views, and in which,

25 Figure 1 is a top elevation of a ratchet wrench constructed in accordance with the invention; Fig. 2, an edge view of same, Fig. 3, a sectional view of the ratchet wheel of the wrench; Fig. 4, a detail perspective 30 view of the work-engaging socket adapted to be engaged by the ratchet wheel; Fig. 5, a longitudinal section of the work engaging socket; and Fig. 6, a modified form of the work engaging socket; and Fig. 7, a detail 35 view showing a modified form of construction of the handle of the wrench with the spaced arms between which the ratchet wheel is mounted formed integral with said handle.

40 Referring to the drawings, the wrench is shown as comprising a stock 10 having a handle 11 provided at one end, and a pair of parallel spaced arms 12 and 13 projecting from the other end. Journaled between the 45 arms 12 and 13 is a ratchet wheel 14 provided centrally with a squared bore 15 which has provided in its wall a continuous groove 16 for a purpose to be presently described.

Pivoted between the projecting arms 12 50 and 13 are the oppositely disposed pawls 17 and 18, the inner ends of which are adapted to be normally forced outwardly by the spring 19 disposed between the ends of said pawls and between the arms 12 and 13.

Mounted on the stock 10, for a rotative 55 movement, adjacent the inner ends of the pawls 17 and 18 is a sleeve 20 which is provided with a laterally extending lug 21 adapted to alternately engage the inner ends of the pawls 17 and 18 as said sleeve is 60 rotated, whereby the outer end of either pawl may be held out of engagement with the teeth of the ratchet wheel.

Detachably mounted in the squared bore 15, of the ratchet wheel, is a work engaging 65 socket 21 also provided with a squared bore 22 and with diametrically opposite, corresponding longitudinal grooves 23 and 24. Mounted in the groove 23 and projecting beyond one end of the socket is a leaf spring 70 25 provided with a laterally projecting lug 26, while a corresponding leaf spring 27, provided with a laterally projecting lug 28 is mounted in the groove 24. The lugs 26 and 28 are so disposed that when the 75 socket 21 is inserted in the bore 15 said lugs will enter the groove 16 under the influence of the expansive force of the leaf springs 25 and 27 and thus lock the socket on the ratchet wheel. In order to detach the socket 80 85 it will only be necessary to grip the projecting ends of the springs 25 and 27 with the fingers and press same toward each other so as to draw the lugs 26 and 28 out of the groove 16 when the socket can easily be withdrawn from the ratchet wheel.

If desired the handle of the wrench may be constructed of two longitudinal sections 30 and 31 which have their corresponding ends reduced at adjacent faces to form the 90 parallel spaced arms 32 and 33 between which may be mounted the ratchet wheel of the wrench and other necessary elements. This form of handle is clearly illustrated in Fig. 7. 95

What is claimed is:—

A ratchet wrench comprising a stock, spaced arms extending from one end of said stock, a ratchet wheel journaled between said arms having a transverse bore therethrough the wall of which is provided with a continuous groove extending transversely of said bore, a work engaging socket adapted to be detachably inserted in the bore of the ratchet wheel and comprising a tubular member corresponding in cross section to the bore of the ratchet wheel and having oppositely disposed longitudinal grooves in 100 105

the outer face thereof, a normally expanded leaf spring mounted in each of said grooves projecting beyond one end of said member, a lug in each of said springs adapted to enter 5 the groove in the wall of the bore in the ratchet wheel when said socket is inserted therein and means for locking said ratchet wheel against independent rotation with

respect to the stock when said stock is oscillated in one direction.

In testimony whereof, I affix my signature, in presence of two witnesses.

CONRAD ROBERT ANDERSON.
